GRINDING MILL

Leonard Dotzer, Brooklyn, N. Y., and George D.
Hugo, Seattle, Wash.

Application February 8, 1936, Serial No. 62,952

7 Claims. (Cl. 83—7)

This invention relates to grinding mills, and more particularly to improvements in mills of that kind used for the reducing of a solid to a desired degree of fineness by a plurality of reductions, or grindings. While the present invention deals more particularly with machines for grinding solids of vegetable origin, such as cocoa nibs, it is not to be construed as being limited thereto, but, rather, it is to be understood as applicable, without material modification, to the grinding of solid, semi-solid, pasty and liquid substances of vegetable, mineral, or of other origin.

In order to impart a better understanding of the present improvements, it will here be explained that grinding mills of the type to which the present invention applies, as heretofore used, comprise grinding elements, or stones, arranged in pairs; that is, requiring two stones for each reduction. These grinding elements, in their most common embodiment, comprise flat faced stones, mounted face to face in axial alignment, and relatively revoluble. Generally one stone is held stationary while the other is rotated, although they both may be rotated in opposite directions. The coating surfaces of paired stones are grooved, ribbed or otherwise processed, whereby to cause the material fed between them for grinding to be advanced outwardly between the stones and ground or reduced during its progression.

Furthermore, in the prior art mills, as employed for instance in the grinding of chocolate, or cocoa, and wherein provision is made for a plurality of reductions or grindings, two stones are employed for each reduction. Thus, for two reductions, four stones are employed, and for three reductions six stones are employed, and it has always been the practice heretofore to feed the material from the center outwardly.

In view of the above, and in view of the fact that it is very desirable that the weight and size of such mills be reduced as much as possible without loss of efficiency or impairing durability, as well as it being desirable also to provide for greater capacity and efficiency in operation, at a lower cost, it has been the principal object of this invention to provide for the utilization of grinding disks or stones in an arrangement whereby the opposite sides of the intermediate stones of an axially aligned set of three or more, are made available for and are used in the grinding of the material passed through the mill.

It has also been an object of this invention to provide a novel manner of grooving the adjacent

or coating surfaces of grinding stones, whereby the material being ground may be caused in certain instances to progress from the outside toward the center of the set; that is, a centripetal movement, as differentiated from a centrifugal travel, so that in a mill arranged for a plurality of reductions, the material may be caused to flow alternately from and toward the axis as it progresses from one set of stones to the other.

Still another object of the invention resides in a modification wherein the grinding stones are disposed in vertical planes instead of being horizontally disposed.

A further object of the invention resides in the manner of mounting the stones of a mill whereby coating grinding surfaces are retained at all times in parallel relation, as differentiated from means provided in prior art devices whereby one of the stones is left free for universal movement to automatically adjust itself to irregularities of the other which might result from various causes.

Still another object of the invention resides in the provision of means for effecting a yielding and adjustable pressure of one stone toward its companion stone to regulate the grind.

Still another object is to provide novel means for adjusting the stones of a mill to spaced relation and for readjusting them to grinding relation in a predetermined order.

Another object resides in the provision of novel means for a forced delivery of partly ground plastic material from one set of stones to another.

Still further objects of the invention reside in those details of construction that permit of an easy and ready removal, or replacement, of one unit of a machine without interference with others.

It is also an object to provide a machine for the grinding of cocoa, chocolate and the like, but adaptable also to the grinding of paints, mustard, lead, flour and the like, and requiring only minor modifications or alterations to change it from one to the other.

Other objects of the invention reside in the novel details of construction, in the combination of parts and in their mode of operation, as will hereinafter be described.

In accomplishing these and other objects of the invention, we have provided the improved details of construction, the preferred forms of which are illustrated in the accompanying drawings, wherein—

Fig. 1 is a side elevation of one type of grinding mill embodied by the present invention.

Fig. 2 is a vertical, cross section view of the same, as seen in its central axial plane.

5 Fig. 3 is a top view of the machine.

Fig. 4 is a partial front elevation, showing the drive shaft and gearing for the rotated stones of the machine.

10 Fig. 5 is a fragmental, perspective view, showing one manner of grooving or processing a surface of a stone of the machine.

Fig. 6 is a horizontal section, taken on the section line 6—6 in Fig. 2.

15 Fig. 7 is a horizontal cross section taken on section line 7—7 in Fig. 2.

Fig. 8 is a sectional detail illustrating the co-acting cam surfaces for lifting the upper stone of the lower unit.

20 Fig. 9 is a similar view showing the coacting cam surfaces for lifting the intermediate stone of the lower unit.

Fig. 10 is a vertical cross section of an alternative construction utilizing an "under feed" for plastic or semi-liquid materials.

25 Fig. 10a is a detail of a mounting for a stationary stone in the machine of Fig. 10.

Fig. 10b is a detail of a stone lifting means in the same machine.

30 Fig. 11 is a vertical cross section of a machine of an alternative type of construction wherein the material to be ground progresses outwardly and then inwardly between successive grinding stones of a series.

Fig. 12 is an elevation of a plural grind, vertical 35 stone mill.

Fig. 13 is an enlarged cross section on line 13—13 in Fig. 12.

Fig. 14 is a plan view illustrating the method of grooving the co-acting surfaces of stones to 40 effect a centripetal movement of ground material.

Referring more in detail to the drawings—

In one of the present forms of construction, embodied by this invention, as shown in Figs. 1 to 45 9, inclusive, there is a fixed, or stationary, frame structure in which two grinding units are operatively mounted. Each of these units, as will later be described, employs three stones with four coacting grinding surfaces. The two units are independent of each other, insofar as their mounting 50 in the frame is concerned, thus to provide for independent removal or replacement, but both units of the machine are here arranged to be driven from a common source of power and provision is made for relaying the partially ground material from 55 one to the other.

The frame structure of this machine comprises four vertical standards, 1, tubular or of other cross sectional form, forming the corners of a rectangular support. At their lower ends, these standards 60 are fixed in bases 2 which may be bolted or otherwise secured to the floor, or other support provided for the machine. At their upper ends, the standards are rigidly fixed in a horizontal spider 3, and intermediate their ends they are likewise 65 joined by a horizontal spider 4. Each of the spiders, 3 and 4, comprises radially extending legs equipped at their ends with suitable mountings 5 which receive, and in which the standards 1 are clamped.

70 Machines of this kind may comprise a plurality of units, and each might comprise two or more stones, according to the capacity desired. In the machine of Figs. 1 and 2, the grinding units are of somewhat different construction. For easy 75 reference, the upper unit is designated in its

entirety by reference character A, and the lower unit is designated in its entirety by reference character B; the upper unit A being identified as a "single grind, double face direct discharge" machine, and the lower unit B being identified as a "double face, center return, successive grind" machine. In accordance with a stated object of the invention, these two units are independent of each other in mounting, and are demountable from the frame to facilitate repair, regrooving, or replacement of stones, and either unit may be removed without interference with the other.

As will be best understood by reference to Fig. 2, the upper unit A is operatively supported in the machine upon a pair of parallel channel beams 7—7, that are fixed horizontally upon the inside of the frame standards. Preferably, the means of attaching the beams 7 comprises clamp bands 8 which embrace the standards 1 and are bolted at their ends to the beams.

The lower unit B, likewise, is supported upon parallel, horizontal beams 10, here shown as resting upon the bases 2 and secured to the vertical standards by clamp collars 11 that embrace the latter and are attached by bolts 12 to the beams.

First describing the construction and mode of operation of the upper unit A: This comprises a horizontal base plate 20 which is supported in the frame structure upon a pair of transverse channel beams 19 which, in turn, rest at their ends upon 3 and are bolted, as at 15 in Fig. 6, to the beams 7—7. The base plate 20 is formed at opposite sides with depending flanges 18 and these fit between and are bolted, as at 18a, to the beams 19. Secured centrally to the under side of the plate 20, 3 is a gear housing 16, removably attached to the base by means of bolts 21 as seen best in Figs. 2 and 6. This housing serves a purpose presently described.

Mounted on this base plate 20, and held against 4 rotation thereon, is the lower grinding stone 22 of this unit. As herein illustrated, the base 20 is circular and has a plurality of radial ribs 20a over which the stone is fitted. Also, the stone is fitted within an upstanding annular flange or shoulder 4 23 on the base 20 concentrically about the axis of the unit. Also a circular plate 24, as an aid in the initial crushing of material is counter-sunk in the top surface of the stone, coaxially thereof and flush with its top surface. Anchor bolts 25 extend 50 downwardly through the plate and stone and at their lower ends are threaded into the base plate 20 to cooperate with longitudinal ribs 20a cast on the base plate to hold the stone and plate 24 securely in place.

Encircling the base 20, concentrically thereof and outwardly spaced from the flange 23 but of higher extent, is a rim flange 26. These flanges together form an annular trough 27 about the stone for the reception of the ground material 60 issuing from between the stones. In the grinding of cocoa nibs, and the like, the ground material will issue from between the stones in the form of heavy liquid or "liquor", and the base of this trough has outlets 28 communicating with conduits or tubes 29 through which the "liquor" or ground material is conducted from the upper to the lower unit of the machine.

Formed centrally of the stone mounting base plate 20, is a bearing 30, through which the lower 70 end portion of a vertical, tubular spindle shaft 31 is slidably fitted, and which lower end portion also extends downwardly through the housing 16 and is slidably contained within an opening 32 in the base of the latter. At its upper end, the 75

spindle shaft 31 is fitted slidably within a central bearing 33 of the top spider 3, permitting vertical adjustment of shaft 31 for a purpose presently explained.

5 Formed on the shaft 31, near its lower end, is an encircling shoulder 35. Also, on the shaft 31, at an interval spaced above the shoulder 35, is an encircling collar 36 fastened to the shaft to serve as the medium of support for a fitting 37 for a purpose presently explained.

10 forms the mounting hub of the upper stone 38 of this unit. This upper stone 38 is rigidly fixed about the fitting 37 concentrically thereof, and is held horizontally disposed thereby with its lower surface in a plane parallel with the plane of the

15 top surface of the next lower stone. Also, this stone is of a diameter equal to that of the two lower stones of the unit and it has an encircling angle iron band 40 fitted and secured about its upper peripheral edge. Studs 41 are fixed to this band 40, and they extend vertically and slidably through guide bearings 42 in the spider frame 3.

This provision of studs holds the top stone against rotative movement, but without hindrance to a vertical adjustment; the purpose of which presently will be explained. Coiled springs 43 are located under compression about the end portions of the studs 41, extended beyond the spider, and they bear at their upper ends against yokes 44 mounted on the spider, and at their lower ends 20 bear against nuts 44a adjustably threaded onto the studs, thereby, through the studs, to yieldingly urge the top stone toward the next lower stone with a pressure that may be increased or decreased, as desired, by adjustment of the nuts 30 44a along the studs, thus to regulate the grinding pressure.

To provide for an accurate, equal and simultaneous adjustment of all nuts 44a, the nuts are in the form of small pinion gears, as will be understood best by reference to Fig. 3, and a ring gear R is disposed concentric of the machine in mesh with all adjusting nuts of the stone, thereby providing that, by a rotative action of the ring gear, all the nuts 44a may be quickly adjusted to 45 place the springs under any desired degree of compression. The ring gear, as will be observed by reference to Fig. 2, has flanges r extended from its top and under surfaces to embrace top and bottom surfaces of the nuts so that the ring gear will be retained in mesh therewith at all times. If desired, sprocket nuts could replace the gear nuts and a sprocket chain belt replace the ring gear, with the same result.

50 Fixed coaxially to the under side of the fitting 37 and countersunk in the stone, to be flush with its under surface, is a ridged plate 45, which contacts with a similar plate 47 on the next lower stone and between which plates the material to be ground is initially received for crushing prior 55 to grinding by the stones.

Interposed between the stones 22 and 38 is the intermediate stone 49. This is mounted by a hub fitting 46 which has a central bearing portion 46a revolvable about the vertical spindle shaft 31. The 60 stone is held rigid on the supporting fitting 46 between face plates 47 and 48 which are countersunk in the upper and lower faces of the stone, respectively, and are riveted to the top and bottom edges of the fitting 46. These plates are 65 grooved, or ribbed, to coat with the plates 45 and 24 of the top and bottom stones to effect the initial crushing or grinding operation of the material entering the machine, and it will be observed that all the grinding plates are of annular 70 form and that the openings through plates 45 and

48, which are the upper plates of their respective sets, are of greater inside diameter than their companion plates and have their inner edge beveled outwardly and downwardly so as to facilitate the feeding of material into the spaces between them.

75 The stone 49 is of a diameter corresponding to that of the other stones of the set and it has a driving ring gear 45a fitted and secured thereto. The ring gear base, together with the outer rim 10 and the connecting web, forms a trough 50 about the stone, and this is adapted to receive therein the ground material issuing as a heavy liquid from between the upper and intermediate stones. The trough base is provided at intervals with discharge openings 51 and the ground material received into the trough is wiped into these openings by fins or paddles 52 that are fixed to the encircling band 40 on stone 38 and which depend into the trough and scrape therealong as the 15 stone revolves.

20 Material to be ground enters the machine at the top through a delivery tube 55 coaxial of the unit. This tube leads into a conical housing 56 which, in turn, is fastened in a closed joint about 25 its lower peripheral edge to the hub portion of the spider 3. This hub portion, about the bearing 33, has passages 57, which receive the material from the housing 56, discharging downwardly into passages 58 formed in the fitting 37 which 30 mounts the stone 38.

To insure an even distribution into the machine of material received from tube 55, a conical distributor 59 is located axially of and directly beneath and spaced from the lower end of the tube 35 55. This distributor is fixed on a vertical shaft 60, revolvably contained coaxial of spindle shaft 31 and extending to the lower end of the latter where it has a driving belt pulley 61 fixed thereto. The lower end of the shaft 60 is contained revolvably in a bushing 62 that is threaded into a central bearing 63 of a spider frame 64 fixed to the lower face of the housing 16. The bushing 62 has a hand wheel 65 formed thereabout whereby it may be rotated to raise or lower the bushing. 40 The bushing bears at its upper end against the hub of the pulley wheel 61, and supports the shaft 60 and thus provides for a vertical adjustment of the shaft 60 by adjustment of the bushing whereby to regulate the spacing of the feed cone 50 59 from the end of tube 55 and thus obtain a desired regulation of delivery of material to the machine.

The material to be ground, when delivered through tube 55, and distributed to the revolving cone 59 to the passage 57, passes directly from the latter into the passages 58 in the hub portion of the fitting 37. The lower ends of the passages 58 partially overlap an annular, downwardly discharging passage 68 coaxially of the 60 hub fitting 46 of the central stone 49 and also partially overlaps the annular grinding plate 47 of the central stone. Thus, through the passage 58, material is fed between the plates 45 and 47 to the coating grinding surfaces of the 65 stones 38 and 49 and also to the passage 68 for delivery between the plates 24 and 48 to the coacting grinding surfaces of the stones 49 and 22.

70 It will be observed that the lower end of the annular passage 68 opens directly to the grinding surfaces between the plates 24 and 48 and the delivery of material to these surfaces is facilitated by the beveling of the inner edge of the plate 48, as shown best in Fig. 2, and the outward feeding of the material between stones is further expe- 75

dited by reason of a certain ridging and grooving of adjacent surfaces, as is indicated in the top surface of the stone 49 as seen in Fig. 5.

It will here be mentioned that while the manner of grooving the coating surfaces of the stones and grinding plates for centrifugal feeding or moving of material forms no part of the invention as applied to the machine of Figs. 1 and 2, it is intended that the grooving should be of a character to effect a progressive and definite feeding of material from its point of reception outwardly to the point of delivery. Fig. 5 illustrates a preferred manner of grooving a crushing plate and stone, but it is to be understood that this is only one of a plurality of methods of grooving that may be employed; the stone here being shown as having the main furrows *f* of radial direction and the spirally directed feather edged cutting grooves *g*.

20 Adjustment of the spacing of the stones for purpose of regulating the fineness of grind, and also a spacing thereof to permit ready feeding of material between the stones at the start of a grinding operation, is provided for through the 25 mediacy of the spindle shaft 31, as will now be described.

It will be observed by reference to Fig. 2, that a worm gear 70 is threaded onto the lower end of shaft 31 and that this gear is fitted rotatably 30 between the lower end of the hub 30 of plate 20 and the lower wall of the housing 16. Thus, the gear 70 supports the shaft 31 and incidentally may, at a certain adjustment, support the upper and intermediate stones by reason of the collars 35 36 and 35 on the shaft. Meshing with gear 70 is a worm 72 on a shaft 73 extended to one side of the machine, see Figs. 1 and 6, and there equipped with a crank 75, or other means, whereby rotary adjustment of gear 70 may be made. By 40 rotary adjustment of the gear 70 in one direction, the shaft 31 may be raised, and incident to this adjustment, the collar 36 will engage fitting 37 and effect the lifting of top stone 38 to a substantial clearance above the intermediate stone 49. Then, a farther lifting of the shaft 31 will 45 effect the lifting of the intermediate stone 49 above the surface of the lower stone 22 by reason of the collar 35 coming into lifting contact with an anti-friction bearing contained on the mounting hub portion 46a of the fitting 46 which mounts the central stone 49.

It will here be stated that starting of the machine, if empty, should be done with the stones spaced apart so that the material may feed between them. Then the stones with material between them are lowered into grinding relation.

Referring now to the lower unit B. This comprises stones in triplicate, designated, respectively, by reference numerals 81, 82 and 83, coaxially mounted by a vertical spindle shaft 84 that is aligned with the axis of the upper unit. The shaft 84 is fixed at its upper end in a central bearing 85 in the spider frame 4, and at the lower end is fixed in a bearing 86 in the base wall 65 of a gear housing 87 presently described.

The lower stone 83 of this unit is mounted by a horizontally disposed base plate 91 which rests upon a pair of spaced parallel cross beams 89-89 which, in turn, rest at their ends upon the channel beams 10-10 to which they are secured by bolts 90 as seen in Figs. 2 and 7. The base plate 70 91 is formed on its under side with depending flanges 88-88 which fit against the inner vertical faces of the cross beams 89-89, and are secured thereto by bolts 88.

The stone mounting base plate 91 is formed with a central hub portion 95 about which the stone is fitted, and it also has an upstanding peripheral flange 91a which fits about the periphery of the stone and is formed also with radial ribs 91b fitted in grooves provided therefor in the lower face of the stone.

The gear housing 87, previously mentioned, is bolted concentrically to the under side of the base plate by bolts 92 and its purpose is to house the 10 stone adjusting gears presently to be described.

The upper stone 81 of the unit is mounted by a hub fitting 96 including a central bearing 96a that receives the vertical shaft 84 slidably therethrough. This fitting has vertical passages 97 therethrough about the bearing, which receive directly thereinto the partially ground material from the upper unit, delivered thereto through the tubes 29. Also, there is an angle iron band 98 fitted about the upper peripheral edge of the 20 stone, and vertical studs 99 are fixed to this band and extended slidably through bearings 100 in the spider 4 to hold the stone against rotation, but permitting vertical adjustment thereof. Springs 101 are located about the upper end portions of these studs, as in the upper unit, and bear against yokes 102, fixed to the spider and downwardly against gear nuts 103 on the studs to urge the stone yieldingly toward the next lower stone; adjustment of pressure being provided for in the adjustment of the nuts 103, thereby to regulate the grind, by a ring gear R as previously described.

The central, or intermediate stone 82 of this set is mounted on a hub fitting 105 that is revoluble about a sleeve 106 which, in turn, is revolubly and slidably fitted about the tubular shaft 84. The upper end of the sleeve 106 is formed with inclined cam surfaces 110 shown in Fig. 8, which rest against complementary surfaces 111 on the under end face of the hub portion 96a. The lower end of the sleeve 106 extends into the gear housing 87 and there has a supporting worm gear wheel 112 keyed thereto. An adjusting worm 113 on a shaft 114 meshes 45 with the gear 112, and this shaft extends from the housing 87 and is provided with a crank 114' or the like, for rotary adjustment of gear 112.

The upper end surface of the hub portion of gear wheel 112 has inclined cam surfaces 112', 50 see Fig. 9, engaging coating cam surfaces 115' on a plate 115 that is supported thereon; the plate having a central opening for passage of the sleeve 106 and having radial legs 117 contained in vertical guides 118 integral with the under 55 face of base plate 91. Ball thrust bearings 120 are interposed between the plate 115 and the lower end of a downwardly extended hub sleeve 121 integral with the hub portion of fitting 105 and fitted slidably about the sleeve 106 and revolubly within the hub bearing 95 of the base casting 91. Thus, an adjustment of the worm gear wheel 112 will effect a rotary action of sleeve 106, and this, by reason of the coaction of cam surfaces 110 at the upper end of the sleeve 106 65 and cam surfaces 111 on the under surface of the hub 96a, will lift the upper stone in the clear above the middle stone. Likewise, the cam surfaces 112' on the upper face of the hub of gear 112, coacting with cam surfaces 115' of plate 115, 70 will cause a lifting action of the plate to effect a similar lifting of the casting 105 and the intermediate stone, to clear the latter from the lower stone.

It is important in this adjustment that the lift 75

of the upper stone be in advance of the lower stone, and also that, on lowering the stone, the top one will be brought to grinding position prior to the middle stone coming to grinding position.

5 The adjustment of the stones for this mode of operation is accomplished by the particular cam design which permits of a continuous rotation of the worm wheel in the same direction. That is, rotation thereof to a certain extent effects 10 the lifting of the stones into spaced relation in their proper sequence. Then, rotation of the wheel through the remaining part of a turn likewise lowers them, in proper sequence, to initial position. The cams might be of various design 15 to accomplish this purpose, and the present invention is not concerned particularly with the design except to the extent that it provides for the lifting and lowering of the stones in proper sequence and to the extent desired.

20 A ring gear 119 encircles and is fixed to the central stone 82 and this, as presently described, is rotatably driven to rotate the stone for a grinding operation; the other stones, being held against rotation as was previously described.

25 Material that is fed to the lower unit through the tubes 29-29 and received as a heavy liquid in the annular, hub passages 97, first is fed to the adjacent grinding surfaces of the stones 81 and 82, passing thereto through the outwardly 30 converging annular space between them which is best shown in Fig. 2.

The ground material, in passing outwardly between stones 81 and 82, finally feeds into an encircling trough 128 formed by the base and outer 35 flange of the ring gear 119, and passes therefrom through openings 130 in the web of the gear into a circular receiving trough 131 underlying the gear and from which conduits 132 lead into the outer ends of horizontal tubes 133 mounted 40 radially of the base 91 with their inner ends opening into an annular chamber 135 of the hub bearing 95. Feed screws 138 are contained in the tubes 133 and are revolvably driven in a direction whereby the material received from conduits 132 is forcibly delivered into the annular 45 chamber 135 to flow upwardly therefrom and to the receiving space between the grinding surfaces of the central and lower stones. The driving means here shown for the feed screws 138 comprises belt pulleys 139 fixed on their outer ends and about which pulleys driven belts 140 operate.

The hub portion of casting 105 is formed with radial fins 105a and these are inclined relative to the direction of rotation so as to act as outward feeders of the material that is forced upwardly from chamber 135, to the space between stones, thereby facilitating distribution of liquor to the grinding surfaces.

Ground material passing outwardly from between these latter stones 82 and 83 is caught in a trough 141 that encircles the lower stone and is conducted therefrom to a point of use, through troughs or tubes as at 142, which lead from the trough 141.

60 Power for driving the machine is applied through a vertical, rotatably driven shaft 150 supported at one side of the machine, as shown in Fig. 4, in bearings 151 and 152. On this shaft are gear pinions 153 and 154 meshing, respectively, with the ring gears 45a and 119 whereby the stones 49 and 82 are rotated.

65 Also, on the vertical shaft 150 is a belt wheel 155 alined with belt wheel 61 and a belt 156 operates about these wheels to drive the distributor shaft 60.

A cross shaft 158, horizontally mounted by bearings 160-160' and 161-161', as seen in Fig. 7, is driven by a spiral gear connection with shaft 150 as designated at 162 in Fig. 7. This cross shaft is equipped at its ends with belt wheels 163-164 alined with the belt wheels 139-139 on the ends of the feed screws 138 and the belts 140 operate thereover to drive the screws as previously explained.

70 While the composition of the grinding stones forms no particular part of the present invention, it is preferred and it is intended that these stones be composed of carborundum, or a like material, since this has been found to be very satisfactory for the intended purpose. However, stones of the usual, or of other composition may be used to advantage.

75 Briefly described, the mode of operation of the above described machine is as follows:

Assuming first that the coating stones of the 20 two units, A and B, have been adjusted into spaced relation for reception of material, the material to be ground is admitted to the upper unit of the machine through the supply tube 55 and is controlled in its flow by vertical adjustment 25 of the feed cone distributor 59, provided for by the hand wheel 65. The material passes into the passages 57 of the top spider and from there is delivered into the passages 58 of the hub fitting 37 of the upper stone 38. Part of the material passes downwardly into the passages 68 of the hub of the intermediate stone 49. The material thus fed to the machine flows outwardly between the coating surfaces of the plates and three stones. Then, by manipulation of the adjusting gear 10, the stones are adjusted into 30 grinding relation. The material ground in the upper unit is emitted from between the surfaces of the upper stone and the intermediate stone into the trough formed by the ring gear 45a, and that 35 emitted from between the intermediate stone and the lower stone is received within the annular trough 27 encircling the lower stone. This latter trough also receives the material from the upper surfaces through the openings 51 in the ring gear. The material received by the trough 27 flows as a heavy liquid through the tubes 29 to 40 the lower unit for its second reduction.

The grind in the first unit is regulated to a 45 certain extent by the surfacing of the stones and by the pressure applied thereto through the 50 mediacy of the springs 43.

Prior to reception of material from tubes 29, the stones of the lower unit B are adjusted to spaced relation. When sufficient material has 55 been delivered between the upper and intermediate stones of this unit to prevent actual contact, they are then lowered into grinding relation. The ground material emitted from between the upper stone and intermediate stone of this unit is received by the trough formed by the ring gear 119 and from there passes into the trough 131 and finally into the conveyor tubes 133 through which it is forced by the feed screws into the chamber 135 to feed upwardly from this chamber to the 60 space between the grinding surfaces of the intermediate stone and the lower stone. These two stones are then lowered into grinding relation and the ground material is emitted from between them into the encircling trough 141, from which 65 it is conducted to its point of use.

70 It is quite apparent that with the machine so constructed, both surfaces of the intermediate stone in either unit, are available for grinding. Also, as seen in unit B, two reductions are accom- 75

plished by use of three stones, whereas, in prior art machines, four stones are required.

In view of the fact that fewer stones are required, it is apparent that the weight of a machine may be materially reduced and without reducing the capacity of number of reductions possible by use of the machine. Furthermore, the cost of providing machines of this character is materially reduced.

It is apparent that in this type of machine, the stones may be arranged in multiples of three or more, and that it then is only a matter of arranging the proper feed to accommodate the cooperating surfaces of adjacent stones. In multiples of two or more, arranged after the fashion of the stones in unit A, it would be only a matter of continuing the feed to supply all surfaces. In multiples of two or more, with a feed arranged as in unit B, wherein the material is delivered successively between the grinding surfaces of successive stones, it would be only a matter of providing for feeding this material from one set to another, and this might be accomplished for multiples of four or more in the same manner as is illustrated in Fig. 2, or, if assuming that certain stones are grooved in a manner to cause the material to feed from the upper set of stones inwardly between the surfaces of the next set, then the progression of material would be continually downward, but would flow outwardly and then inwardly in successive grindings as it progressed from the upper to the lower stones.

In the present construction, as was an object of the invention, the stones are held in parallel relationship by their slideable mounting on the central shaft, and are urged yieldingly together under an adjustable pressure by the provision of the springs associated with the upper stone. This is believed to be a novel feature in view of the fact that, heretofore, it has been the common practice to mount one of the stones loosely for universal adjustment thereby permitting it to automatically accommodate itself to unevenness of wear on one or both of the stones.

Various modifications and alternatives will now be described:

In Fig. 10 we have illustrated a type of machine, known as an "under fed" mill. In this construction, we utilize a plurality of horizontal stones, arranged in vertical, coaxial alignment about a central driving shaft 170. The shaft is revolvably contained at upper and lower ends, respectively, in bearings 171 and 172 of a suitable frame structure. The five stones, herein shown, and designated by reference characters 173, 174, 175, 176 and 177 may be of the usual form of construction for centrifugal movement of ground material. The stones 173, 175 and 177 are held against rotation by guides 178 fixed thereto and slideable along vertical shafts 180 rotatably supported in the frame structure. Also, the stones of this set may be lifted into spaced adjustment by means of collars 181 that are fixed on the vertical shafts 180. The collars 181 which are to lift the non-rotating stones 173 and 175 are adapted to be lifted by the shafts 180 against the guide blocks 178 of these stones, while the collars 181', which are to lift the rotating stones, comprise sleeve portions which have bearings 179 rotatable thereon and arranged to be lifted by the collars into lifting abutment with shoulder bands 181a that encircle and are fixed to these stones.

In order to insure a pressure of the series of stones toward each other sufficient for the grinding operation, coiled springs 183 are located about

the shafts 180 to bear against collars 184 on the shafts, and against the guide lugs 178 which are fixed to the uppermost stone.

As here shown, the stones 174 and 176 are keyed to the shaft 170 for rotation thereby, and this shaft may also be used if desired to effect an adjustment of the stones into spaced relation by the following means: Keyed on shaft 170, near its upper end is a gear 190, and keyed on the shafts 180 are gears 191 of like size meshing with gear 190. A clutch disk 195 is fixed on gear 190 and a clutch drum 196 is slidably keyed on shaft 170 and movable by a shift lever 197 into holding contact with the disk to cause the gear 190 to be rotated. This causes rotation of gears 191 and shafts 180, which latter are threaded at their lower ends into the frame structure, as at 198 in Fig. 10. Rotation of shafts 180 causes them to travel upwardly and thus to cause the collars 181 to engage in succession with shoulders of the stones from top to bottom of the set, thus to lift the stones into spaced relation. A spring 199 urges the clutch drum to non-driving position when released by lever 197.

The material received as a liquid to be ground is here forced through a conduit 182, upwardly through a passage 183 in the hub mounting of the lower stone, into the intervening space between the grinding surfaces of stones 176 and 177. From this space excess material is forced upwardly, by reason of the feeding pressure, into the intervening spaces between the upper stones. To provide for this upward flow, the mounting hub 185 of stone 174 has passages 186. Stone 175 likewise has a central passage 187 and the hub member 188 of stone 176 has passages 189. In this construction of Fig. 10 there is no overflow opening at the top of the unit and therefore the rate of delivery of ground material would be governed by regulating the flow through pressure feed pipe 182.

In Fig. 11 there has been illustrated, in cross section, another modification of a grinding mill employing three stones for two reductions, and whereby both a centrifugal and a centripetal movement of material is accomplished, thus to simplify the machine. This machine comprises base supports 210-211 which mount an enclosing housing 212 for the three stones which are designated, respectively, by reference numerals 215, 216 and 217. These stones are in vertical axial alignment and the upper and lower stones are held against rotation within the housing while the intermediate stone is revolvably driven. As will be observed, the upper stone has a hub casting 220 with vertical passages 221 into which material is delivered from a supply tube 222. From the passages 221, the material is delivered into the outwardly converging annular space 223 between the stones 215 and 216 for grinding in its centrifugal movement to the periphery of the stones. On issuing from between the upper set of stones, it flows downwardly and, by the enclosing housing, is delivered into the annular, inwardly converging space 224 between the stones 216 and 217 for a centripetal movement and on being emitted from between these stones passes into discharge openings 225 of a hub casting 226 in the lower stone and is delivered therefrom to a housing 227 for delivery from the machine.

In the mechanism illustrated, the central stone has a hub fitting 228 revolvable on a central, tubular shaft 229, the latter being revolvably contained in a tubular sleeve 230 that is slidably fitted in a bearing in the base casting 226. The stone

216 also has a ring gear 246 fitted thereabout and meshing with a driving gear 231 on a shaft 232.

Vertical adjustment of the upper and intermediate stones is provided for in the vertical movement of their mountings. Sleeve 229 is adjustable through the mediacy of a worm gear 234 threaded on its lower end, and likewise, a vertical adjustment of sleeve 230 by a worm gear 233 threaded onto its lower end.

10 It is to be understood that in this, as well as in other modifications of the mill, the driving of the stones, their mode of adjustment, the feeding and delivery of material, etc., may be accomplished in various ways and therefore it 15 is not the intention that the disclosures should in any way restrict the claims to the details shown. However, in the mills using the centripetal feeding of material, it becomes necessary to groove, or process the stones in a manner that 20 will not only overcome the tendency to feed or force the material outwardly by reason of centrifugal action, but which will actually induce an inward flow, such for instance as is required with reference to the stones 216 and 217 in Fig. 11.

25 In Fig. 14, there has been illustrated a method of grooving stones to effect the centripetal movement of ground material, and it is intended that this shall be applied to the machine of Fig. 11. In Fig. 14, 245 and 246, respectively, designate 30 upper and lower stones of a pair arranged for centripetal feeding of material and the arrows placed thereon designate their direction of relative rotation. Each stone is provided about the peripheral portion of its grinding surface with 35 relatively large furrows 248 all extending circumferentially in the same direction, and tapered toward their inner ends, and opening toward the direction of rotation as effective collectors of material. The mouths of the furrows which open 40 to the periphery of the stone are quite wide to facilitate scooping up the material to be ground. Between the furrowed area of the disk and the central part, the disk is closely grooved. These 45 grooves 250 are slightly volute in direction and receive the material from the furrows to deliver it toward the axis of the stones, by reason of pressure of material gathered by the large mouths of the furrows and grooves.

It will here be explained that the direction of 50 grooving in the surface of each stone is the same, but, since one is inverted and placed face down on the other, the direction of grooving in one then angularly crosses that of the other. Therefore, when the stones are rotated in opposite directions, or when one is rotated and the other held 55 stationary, the grooving in one has a sort of shearing action across the grooving of the other toward the central axis of the stones and this effects an inward conveyance or pressure against 60 the material as will be quite obvious. The normal centrifugal tendency is overcome by this manner of grooving and when both stones are rotated, in opposite directions, the speed of rotation may be reduced to one-half that required where only 65 one is driven. Feeding is facilitated also due to the fact that in this type of mill, the mouths of the furrows are flooded with the material to be ground by reason of the enclosing housing, such as the housing 212 in the device of Fig. 11.

70 In Figs. 12 and 13 is illustrated what is identified as a vertical stone mill. In this arrangement there is a plurality of units, X, Y, Z, successively at lower elevations, and the stones in each of the several units are supported on a horizontal axis, 75 in a suitable frame. In the detailed illustration

of one of the units, as seen in Fig. 13, the stones are designated by reference characters 261, 262 and 263. The outer stones 261 and 263 are stationary, but the center stone is rotatably driven by its supporting shaft 265, which is revolubly mounted on the frame structure. The material to be ground is fed under pressure into the space between the stones 261 and 262 from a supply pipe 267, which opens into the tubular hub 269 which mounts the stone 261. Part of the material delivered passes through openings 268 in the hub portion 268a of the central stone into the receiving space between the center stone and the opposite side stone 263. A housing 270 surrounds the stones and receives the ground material which is emitted from between the stones. This material is discharged through a delivery pipe 271. Any suitable frame structure may be provided to support the driving shafts of the units and the shafts may be driven by any suitable means.

It will be mentioned here that machines of this latter type may be made in single units or in a series of units, as in Fig. 12, and material delivered by gravity or forced flow from one to the next succeeding one.

25 In each of the machines described, provision has been made for utilizing both sides of intermediate stones for a grinding operation. Thus, the object of reducing weight, size and cost has been accomplished. Furthermore, a more expeditious handling of material is made possible by the feed devices shown and also in the provision made for centripetal movement where this is desired.

Having thus described our invention, what we claim as new therein and desire to secure by Letters Patent is:

1. A grinding mill comprising a series of three or more parallel faced stones arranged in vertical coaxial alignment and yieldingly in face to face contact, means for causing relative rotation of adjacent stones, means for introducing material between opposed faces for grinding and an axial support for the stones movable in its axial direction and having means thereon to cause the stones to be lifted into spaced relation 40 successively from the upper stone downwardly and to be lowered into grinding relation successively from the lower stones upwardly.

2. A top feed grinding mill comprising a frame structure, an axial shaft supported vertically 50 thereby for longitudinal adjustment, a series of parallel faced grinding stones mounted about the shaft for relative rotation and successively in face to face opposition, each stone having a hub bearing fitted to the shaft whereby the 55 stones are held rigidly and operatively in parallel relation, means for effecting an upward longitudinal movement of the said shaft, and shoulders on said shaft engageable with the hub bearings of the stones when said shaft is adjusted upwardly to effect the lifting of the stones of the series into spaced relation successively from the upper stones downwardly, and when the shaft is lowered to lower the stones into 60 grinding relation successively from the top stone 65 downwardly.

3. A device as in claim 2 wherein the said axial shaft is keyed against rotation in the frame and wherein the means for effecting the longitudinal travel of said shaft comprises a 70 gear wheel threaded thereon and held in the frame against movement in a direction axially of the shaft, and means is provided for rotating said gear to longitudinally adjust the shaft by reason of its threaded connection.

4. In a grinding mill of the character described, three grinding stones arranged coaxially about a vertical axial member, successively in face to face contact, means for effecting a relative rotation of adjacent stones for the grinding of material between opposed faces, means for feeding material through the upper stone to the coating faces of the central and upper stones for reduction and for a centrifugal discharge of material, means for collecting the material as it is emitted from between the said central and upper stones, and means for delivering the collected material upwardly through the lower stone to the coating surfaces of the central and lower stones for a further reduction.
5. In a grinding mill of the character described, three parallel faced grinding stones arranged coaxially about a vertical axial member, successively one above the other, and yieldingly in face to face opposition, means for effecting a relative rotation of adjacent stones for the reduction of material introduced between opposed faces; the upper stone having a hub mounting with openings therethrough for the delivery of material to the coating surfaces of the upper and central stones for reduction and centrifugal delivery, a mounting for the lower stone having openings directed upwardly therethrough and communicating with the space between the grinding faces of the central and lower stones, and means for effecting a forced delivery of material from the first set of faces upwardly through the said openings to the second set of grinding faces for centrifugal delivery therefrom.
6. In a grinding mill of the character described, a series of parallel faced grinding stones arranged coaxially about a vertical, tubular axial

member, and successively in face to face opposition; said stones having mounting hubs fitted to said axial member, and having registering annular feed passages therethrough from face to face of the stones and through which material may be supplied to all the grinding surfaces, the annular passages being in communicating relationship for continuous flow of material therethrough to the several grinding surfaces, a hopper, a supply tube entering said hopper, a distributor disk supported below the delivery end of the tube, a revolubly driven supporting shaft for said disk, and means for longitudinally adjusting the shaft to move the disk toward or from the tube outlet to determine the delivery of material therefrom.

7. In a mill of the character described, a series of three grinding stones arranged coaxially of a vertical axial member yieldingly in face to face opposition, means for effecting a relative opposite rotation of the central stone with reference to the upper and lower stones, means for feeding material between the coating surfaces of the central and upper stones at a central point for centrifugal delivery, means for feeding the material from the first set of stones between the opposed surfaces of the lower set of stones for a second reduction and centripetal delivery; the opposed surfaces of the coating stones having grooves therein from their outer to the medial portions arranged with those of one surface angularly crossing those of the other and so directed that relative rotation of said stones causes coaction of the grooved surfaces whereby the direction of delivery is determined.
